UNITED STATES PATENT OFFICE

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF TRAIN BRAKES

Application filed April 4, 1930. Serial No. 441,593.

My invention relates to apparatus for the control of railway train brakes, and has for an object the provision, in combination with the usual engineer's valve on the locomotive, of auxiliary brake controlling mechanism at another point on the train capable of reproducing the functions of the engineer's valve, and means for causing the condition of such auxiliary mechanism to register with the positions of the engineer's valve.

I will describe several forms of apparatus embodying my invention, and will then point out the novel features thereof in claims.

In the accompanying drawings, Fig. 1 is a diagrammatic view showing one form of locomotive-carried apparatus embodying my invention for transmitting influences to the auxiliary mechanism. Fig. 2 is a diagrammatic view showing one form of auxiliary mechanism located at another point on a train for reproducing the functions of the engineer's valve, together with means responsive to the influences transmitted by the locomotive-carried apparatus for controlling such mechanism, all embodying my invention. Fig. 3 is a diagrammatic view showing one form of apparatus located at a second point on the train and controlled by the auxiliary mechanism for transmitting influences to the locomotive to indicate to the engineer the condition of the auxiliary mechanism. Fig. 4 is a diagrammatic view showing one form of locomotive-carried apparatus responsive to the influences transmitted from the second point on the train for indicating to the engineer the condition of the auxiliary mechanism. Fig. 5 is a diagrammatic view showing a modification of a portion of the apparatus shown in Figs. 1 and 3, which modification may be used when the influences from the locomotive to the second point on the train and/or vice versa are transmitted by radio.

Similar reference characters refer to similar parts in each of the views.

Referring first to Fig. 1, the reference character B designates the usual engineer's brake valve having a handle 67 capable of assuming the usual functional positions known as "release", "running", "lap", "service" and

"emergency." Operatively connected with the handle 67 of the brake valve B is a circuit controller E, comprising a contact member 52 which moves with the brake valve handle, a fixed contact member 16 with which the member 52 constantly engages, and a plurality of fixed contact members 17, 18, 19 and 20. When the engineer's brake valve handle is in the release position, the contact member 52 engages with member 17. When the handle is in the running position, the movable member 52 engages with fixed member 18. When the handle is in the lap position the movable member 52 engages the fixed member 16 but does not contact with any of the other members of the circuit controller. The member 52 engages contact member 19 or 20 according as the engineer's brake valve handle is in the service or the emergency position.

Located on the locomotive is a generator F of alternating carrier current, the frequency of which may, for example, be 3500 cycles per second. As here shown, this generator is of the vacuum tube oscillator type, comprising an electron tube T^F containing the usual filament 1, grid 2, and plate 3. The filament 1 is constantly heated by a battery 36, and the tube is provided with a grid circuit including a reactor 5. The tube is also provided with a plate circuit including a battery 4, and the primary 6 of a transformer 9. Connected in series with the reactor 5, battery 4, and primary 6, is a condenser 68. In accordance with usual practice, the windings 5 and 6 are closely coupled to provide for mutual inductance between them, although to simplify the drawings they are shown spaced apart. The output frequency of the generator F is determined by the characteristics of the condenser 68, the reactor 5, and the primary 6. The secondary 7 of transformer 9 is included in a series circuit with two windings 26 and 27 located in inductive relation with the two track rails 28 and 29, respectively, which circuit is tuned by a condenser 32 to the output frequency of the generator F.

Also located on the locomotive is a second generator M, which I will term a "modula-

- tion" generator, because its output is used to modulate the high frequency output of the generator F. Generator M is, likewise, of the electron tube oscillator type, comprising 5 a tube T^* , together with a reactor 69, a battery 8 and a transformer primary 12, all of which are associated with the tube T^* in the same manner as the corresponding elements, 10 5, 4 and 6 of the generator F. Windings 12 and 69 are closely coupled to each other for the reason stated above in discussing windings 5 and 6. The secondary 13 of the transformer 10 is connected with the primary 14 of a transformer 11, the secondary 15 of 15 which is included in the grid circuit of the carrier current generator F, whereby the output of the generator F is modulated at the frequency of the current delivered by generator M.
- 20 The frequency of the output of the modulation generator M is determined by condensers 22, 23, 24 and 25, of different capacities, one or another of which is connected in series with elements 69, 8 and 12 according to the 25 condition of the circuit controller E. When the engineer's brake valve is in the release position, condenser 22 will be connected with the generator M, and this condenser may be so adjusted that the oscillation frequency of 30 the generator M will be 80 cycles per second. When the engineer's valve is in the running position, condenser 23 is connected with the modulation generator, and this condenser may be so adjusted that the oscillation frequency will be 150 cycles per second. When the engineer's valve is in the service position, condenser 24 will be connected with the modulation generator, and this condenser may be so proportioned that the oscillation 35 frequency will be 350 cycles per second. When the engineer's valve is in the emergency position, condenser 25 will be connected with the modulation generator, and this condenser may be so adjusted that the oscillation frequency will be 500 cycles per 40 second. When the engineer's valve is in the lap position, the condenser circuit is opened and the carrier current delivered by the generator F will be unmodulated. It follows 45 from the foregoing, that the output current of generator F will be modulated at 80, 150, 350 or 500 cycles per second, according as the engineer's brake valve is in the release, running, service or emergency position, and 50 that the output of generator F will be unmodulated when the engineer's valve is in the lap position. It is understood that all of the frequencies hereinbefore mentioned are chosen for purposes of illustration only, and 55 that frequencies differing widely therefrom may equally well be used.
- 60 It will be observed that by means of the apparatus shown in Fig. 1, power is delivered to the track rails in the form of a carrier current either unmodulated or modulated at any 65 one of four different frequencies, and that each of these conditions corresponds to a functional position of the engineer's brake valve B.
- Referring now to Fig. 2, the apparatus 70 which is shown in this view is located at a second point on the train, which point may, for example, be the caboose of a freight train. This caboose is provided with a main reservoir M^* , a feed valve F^* , and a plurality of 75 electromagnetic valves D arranged to reproduce the functions of the engineer's valve. Of course, the caboose will necessarily be provided with further apparatus, such as a compressor Q, pressure gauges, governors, etc., 80 similar to the apparatus carried on the locomotive, but the independent brake valve, together with its auxiliary equipment, is not needed. Each valve D is biased to the closed position, and is opened when its associated 85 magnet 70 is energized. When valve D^c is opened, that is, when its magnet 70 is energized, main reservoir M^* will be connected with the brake pipe BP, so that the apparatus will then reproduce the condition which exists 90 on the locomotive when the engineer's valve is in the release position. When the valve D^r is open, the brake pipe is connected with the feed valve F^* , thereby reproducing the condition existing on the locomotive when the 95 engineer's valve is in the running position. When the valve D^s is open, the brake pipe will be connected with atmosphere through 100 an orifice of such characteristic as to produce a reduction in brake pipe pressure at substantially the service rate of the usual brake valve to effect a service application of the 105 brakes. When valve D^e is open, the brake pipe will be connected with atmosphere through an orifice of such characteristic as to cause an emergency rate of reduction in brake pipe pressure and an emergency application 110 of the brakes. The magnets of the valves D are controlled by apparatus which I will now 115 describe.
- The caboose is provided with a receiving circuit comprising two windings 30 and 31 located in inductive relation with the two track rails 28 and 29, respectively, which windings are connected through a condenser 33 with a portion of a reactor 34, this circuit being tuned to the frequency of the carrier current produced by generator F on the locomotive. The reactor 34 is connected with a condenser 35, and these two elements are, 120 likewise, tuned to the frequency of the carrier current. This apparatus, therefore, constitutes a filter G having two stages, both of which are tuned to the frequency of the carrier current, and the filter therefore serves 125 to prevent influence of current from other sources of power on the apparatus for controlling the valves D. The voltage across the terminals of the condenser 35 is applied 130 to the grid circuit of a first amplifier tube A^1 ,

and this grid circuit includes the usual "C" battery 75. The plate circuit for this tube includes a battery 45 and a reactor 39. The output of this amplifier is connected with the grid circuit of a second amplifier A², the two amplifiers being coupled by a tuned circuit consisting of a condenser 37 and a reactor 38. A "C" battery 76 is included in the grid circuit for amplifier A². The plate circuit of the amplifier A² includes the battery 45 and a reactor 41. The plate circuit of the amplifier A² is tuned by a condenser 40 and a reactor 42 to the frequency of the carrier current. From suitable points on the reactor 42, the power is fed into a demodulating full-wave rectifier 43, the output of which is supplied to the primary of a low frequency transformer 44. The output of this transformer, which is of the modulation frequency, is applied to the grid circuit of a third amplifier A³, through a "C" battery 77, and the plate circuit of this amplifier includes the battery 45 and a reactor 46, as well as the primary of a transformer 49. The plate circuit of the amplifier A³ is not tuned, but it includes a blocking condenser 48 of large capacity. The secondary of transformer 49 is connected with a plurality of parallel, tuned, condenser-reactor combinations K, each consisting of a condenser 50 and a reactor 51.

The natural frequencies of the condenser-reactor combinations K correspond to the frequencies delivered by the modulation generator M on the locomotive. Combination K^c responds to a frequency of 80 cycles per second, K^s to a frequency of 150 cycles per second, K^e to a frequency of 350 cycles per second and K^g to a frequency of 500 cycles per second.

A portion of the reactor 51 of combination K^c is connected with the input terminals of a full-wave rectifier 52, the output terminals of which are connected with the operating magnet 70 of valve D^c. In a similar manner the magnets of valves D^s, D^e, and D^g are supplied with power from combinations K^s, K^e and K^g respectively.

The operation of the apparatus shown in Figs. 1 and 2, is as follows: When the engineer's brake valve B is in the running position, the carrier current will be modulated at 150 cycles per second, so that valve D^c on the caboose will be open, with the result that the auxiliary brake controlling mechanism will, likewise, be in the running condition. Similarly, when the engineer's brake valve is in the release, service, or emergency position, the carrier current will be modulated at 80, 350 or 500 cycles per second, with the result that on the caboose valve D^c, D^s or D^e will be open, so that the auxiliary mechanism will register with the position of the engineer's valve. When the engineer's valve is in the lap position, the carrier current will be unmodulated, so that all of the valves D

on the caboose will be closed, with the result that the auxiliary mechanism will, likewise, be in the lap condition.

In the actual practice of my invention as thus far described, it will probably be desirable to provide indicating apparatus on the locomotive controlled by the auxiliary brake mechanism on the caboose, so that the locomotive driver will know whether or not the condition that he has set up on the locomotive is being duplicated in the caboose, and so that, if it is not being duplicated, he can handle the train accordingly. This necessitates the provision of transmitting apparatus on the caboose and receiving apparatus on the locomotive, and it also necessitates a different frequency for indication from that which is used for the transmitting of influences from the locomotive to the caboose. It will be noted in Fig. 2 that each valve D is provided with a contact 53 associated with a moving part of the valve and arranged to be down or up according as the valve is closed or open.

Referring now to Fig. 3, the caboose is provided with a generator F₁ of carrier current and a generator M₁ of modulating current, which generators are similar in all respects to the corresponding generators on the locomotive. The output of the carrier current generator F₁ may, for example, be 4500 cycles per second, and the output of the modulation generator M₁ may be 80, 150, 350, 500 or 700 cycles per second, according as a condenser 54, 55, 56, 57 or 58 is connected with this generator. When the charging valve D^c of Fig. 2 is open, contact 53^c will be up, so that condenser 54 will be connected with the modulation generator, and the carrier current delivered by the generator F₁ will then be modulated at 80 cycles per second. Similarly, condenser 55, 56 or 57 will be connected with the modulation generator according as valve D^s, D^e or D^g is open, with the result that the carrier current will be modulated at 150 cycles, 350 cycles or 500 cycles per second. When all of the valves D are closed, so that the auxiliary braking equipment is in the lap condition, all four of the contacts 53 will be down, so that condenser 58 will be connected with the modulation generator M₁, with the result that the output of the carrier current generator will be modulated at 700 cycles per second.

Referring now to Fig. 4, the locomotive is provided with a receiving circuit comprising two windings 30 and 31 located in inductive relation with the two track rails 28 and 29, respectively, which windings are connected with a filter G through a condenser 33, by which the receiving circuit is tuned to the frequency of the carrier current generator F₁. Filter G may be in all respects similar to the corresponding filter shown in Fig. 2. The output of the filter G is supplied

to amplifying and demodulating apparatus H, which may, likewise, be similar to the corresponding apparatus shown in Fig. 2. The output of this apparatus H is supplied 5 to the primary of transformer 49, the secondary of which furnishes power to a plurality of condenser-reactor combinations K₁, similar in all respects to the combinations K of Fig. 2. These combinations K₁ are tuned to respond 10 respectively to 80, 150, 350, 500 and 700 cycles per second. Each combination K₁ supplies current to a rectifier 52, and each rectifier in turn supplies current to a relay J. These relays control five indicator lamps L^c, 15 L^R, L^s, L^E and L^L, indicating, when lighted, "release", "running", "service", "emergency" and "lap", respectively. When the charging valve D^c on the caboose is open, relay J^c will be energized, so that current will be supplied 20 to lamp L^c, by a circuit which passes from terminal X of a suitable source of current, through the front point of contact 62 of relay J^c and lamp L^c to terminal O of the same source of current. Similarly, when relay J^R 25 is energized in response to operation of valve D^R, lamp L^R will be lighted, the circuit being from terminal X, through the back point of contact 62 of relay J^c, front point of contact 62 of relay J^R and lamp L^R to terminal O. In 30 similar manner lamp L^s or lamp L^E will be lighted in response to energization of valve D^s or D^E. When all of the valves D are de-energized, so that the output of generator F₁ is modulated at 700 cycles per second, relay 35 J^L will be energized, with the result that lamp L^L will be lighted, thereby indicating that the auxiliary brake controlling mechanism in the caboose is in the lap condition.

The transmission of current between two 40 points on a train through the medium of the track rails may be accomplished in the manner disclosed in my copending application Serial No. 450,135, filed May 6, 1930, for electric train signaling systems, and in my application Serial No. 269,148, filed April 11, 45 1928, for electric train signaling systems, of which the said application Serial No. 450,135 is a continuation in part.

Referring now to Fig. 5, I have here shown 50 a modification of the locomotive transmitting apparatus suitable for use when the influences between the locomotive and the caboose are transmitted by radio. Instead of connecting the secondary 7 of transformer 9 with windings associated with the track rails, one terminal of this secondary is connected with ground 63, and the other terminal is connected with an antenna 64. The receiving apparatus on the caboose will, of course, be modified in the same manner, and the same 55 thing will be true of the indication transmitting apparatus on the caboose and the indication receiving apparatus on the locomotive. No other changes are required, except to substitute air core reactors for iron core reactors 60 65

in the carrier current circuits, and to introduce a grid leak 65 and a condenser 66 in the grid circuits of the carrier current generators T^r. Of course, the carrier frequencies will be radically different from those which are used 70 when the influences are transmitted through the track rails, but this merely means adjusting the elements associated with the carrier current generators, so that the tubes of these generators will oscillate at radio frequencies. 75

Although I have herein shown and described only a few forms of apparatus embodying my invention, it is understood that various changes and modifications may be made therein within the scope of the appended claims without departing from the spirit and scope of my invention. 80

Having thus described my invention, what I claim is:

1. Apparatus for the control of train 85 brakes comprising, in combination with the usual engineer's valve on the locomotive, a source of carrier current on the locomotive, means for modulating the output of said source at different frequencies for different 90 positions of said engineer's valve, auxiliary brake controlling mechanism at another point on the train capable of reproducing the functions of the engineer's valve, and controlling 95 means associated with said auxiliary mechanism and selectively responsive to the several 100 modulations of said carrier current for causing the condition of the auxiliary mechanism to register with the position of the engineer's 105 valve.

2. Apparatus for the control of train 110 brakes comprising, in combination with the usual engineer's valve on the locomotive, auxiliary brake controlling mechanism at another point on the train capable of reproducing the functions of said engineer's valve, transmitting means on the locomotive including a source of high frequency carrier current, means for modulating the output of said 115 source at different frequencies for different 120 positions of the engineer's valve, receiving means at said second point, and demodulating means associated with said receiving means for causing the condition of said auxiliary mechanism to register with the position of the 125 engineer's valve.

3. Apparatus for the control of train 130 brakes comprising, in combination with the usual engineer's valve on the locomotive, transmitting means on the locomotive including an oscillator generating a high frequency carrier current, modulating means on the locomotive including an oscillator generating low frequency modulating currents, means for coupling the plate circuit of said modulation oscillator with the grid circuit of said carrier current oscillator, a plurality of multiple shunts for the tuning circuit of said modulation oscillator including condensers of different capacities, means for closing dif- 135

ferent ones of said shunts for different functional positions of said engineer's valve, and auxiliary brake controlling mechanism at another point on the train selectively responsive to the several modulations of said carrier current.

4. Apparatus for the control of train brakes comprising, in combination with the usual engineer's valve on the locomotive, transmitting means on the locomotive including an oscillator generating a high frequency carrier current, modulating means on the locomotive including an oscillator generating low frequency modulating currents, means for coupling the plate circuit of said modulation oscillator with the grid circuit of said carrier current oscillator, means for varying the output frequency of said modulation oscillator according to the functional positions of said engineer's valve, and auxiliary brake controlling mechanism at another point on the train selectively responsive to the modulation frequencies of said carrier current.

25 5. Apparatus for the control of train brakes comprising, in combination with the usual engineer's valve on the locomotive, means on the locomotive for transmitting a carrier current modulated at different frequencies for different functional positions of the engineer's valve, means at another point on the train for receiving such modulated current, a plurality of multiple circuits receiving current from said receiving means and tuned respectively to said different modulation frequencies, and auxiliary mechanism including valves controlled by said circuits for reproducing the functions of said engineer's valve.

40 6. Apparatus for the control of train brakes comprising, in combination with the usual engineer's valve on the locomotive, auxiliary brake controlling mechanism at another point on the train capable of reproducing the functions of the engineer's valve, means for causing the condition of said auxiliary mechanism to register with the position of the engineer's valve, and indicating means on the locomotive controlled by said auxiliary mechanism for indicating when the mechanism has reproduced a function of the engineer's valve.

7. Apparatus for the control of train brakes comprising, in combination with the usual engineer's valve on the locomotive, auxiliary brake controlling mechanism at another point on the train capable of reproducing the functions of the engineer's valve, means for causing the condition of said auxiliary mechanism to register with the position of the engineer's valve, transmitting means including a generator of high frequency carrier current and a generator of modulating current at said second point, means for varying the frequency of the output of said modu-

lation generator according to the condition of said auxiliary mechanism, means on the locomotive receiving the modulated current delivered by said transmitting means, demodulating apparatus associated with said receiving means, and signals controlled by said demodulating apparatus.

8. Apparatus for the control of train brakes comprising, in combination with the usual engineer's valve on the locomotive, transmitting means on the locomotive including a source of carrier current of one frequency modulated at different lower frequencies corresponding to different functional positions of the engineer's valve, auxiliary brake controlling mechanism at another point on the train selectively responsive to the frequencies of modulation of said carrier current to reproduce different functions of the engineer's valve, transmitting means at said second point including a source of carrier current of another frequency modulated at different lower frequencies corresponding to the several functional conditions of said auxiliary mechanism, and signaling apparatus on the locomotive selectively responsive to the frequencies of modulation of said second carrier current.

9. Apparatus for the control of train brakes comprising, in combination with the usual engineer's valve on the locomotive, means for impressing on the track rails a carrier current modulated at different frequencies corresponding to different functional positions of said engineer's valve, and auxiliary brake controlling mechanism at another point on the train receiving energy from the track rails and selectively responsive to said modulated current to reproduce such functions of the engineer's valve.

10. Apparatus for the control of train brakes comprising, in combination with the usual engineer's valve on the locomotive, a radio transmitter on the locomotive, means for supplying said transmitter with a carrier current modulated at different frequencies corresponding to different functional positions of said engineer's valve, a radio receiver at another point on the train, and auxiliary brake controlling mechanism controlled by said receiver and selectively responsive to the modulations of said carrier current to reproduce the functions of said engineer's valve.

11. Apparatus for controlling the brakes on a train of cars comprising a train brake pipe, an engineer's brake valve device on one car of the train operable to effect variations in brake-pressure, a reservoir on at least one car of the train, means on said car for compressing fluid into said reservoir, and means operable upon movement of said brake valve device for supplying fluid under pressure from said reservoir to the brake pipe.

12. Apparatus for controlling the brakes on a train of cars comprising a train brake

pipe, an engineer's brake valve device on one car of the train operable to effect variations in brake pipe pressure and having a position in which fluid under pressure is supplied to 5 the brake pipe, a reservoir on another car of the train, means on said other car for compressing fluid into said reservoir, and means operable upon movement of said brake valve device to said position for supplying fluid 10 under pressure from said reservoir to said brake pipe.

13. Apparatus for the control of train brakes comprising, in combination with a 15 brake pipe and an engineer's brake valve on the locomotive for effecting variations in brake pipe pressure, an independent source of fluid under pressure on a car of the train, and means including apparatus on said car responsive to movement of said brake valve 20 device for supplying fluid under pressure from said source to the brake pipe.

14. Apparatus for the control of train brakes comprising, in combination with a 25 brake pipe and an engineer's brake valve on the locomotive for effecting variations in brake pipe pressure, a reservoir on a car of the train, means on said car for compressing fluid into said reservoir, and means operable upon movement of said brake valve device for 30 supplying fluid under pressure from said reservoir to the brake pipe.

15. Apparatus for the control of train 35 brakes comprising, a plurality of brake pipe pressure controlling mechanisms located at different points on a train each involving a local air compressor and each capable of causing the usual variations in brake pipe pressure, and manually controlled means for causing each of said brake pipe pressure controlling mechanisms to simultaneously vary the brake pipe pressure in the same manner.

16. Apparatus for the control of train 45 brakes comprising; two brake pipe pressure controlling mechanisms located at different points on a train each involving a local air compressor and each capable of varying the brake pipe pressure to produce "release", "running", "lap", "service" and "emergency" 50 conditions; and manually controlled means for causing the two brake pipe pressure controlling mechanisms to produce simultaneously the same variations in brake pipe pressure.

55 17. Apparatus for the control of train brakes comprising, in combination with the usual brake pipe and brake devices on a train, a plurality of brake pipe pressure controlling mechanisms located at different points on 60 a train each involving a local air compressor and each capable of producing the several conditions of brake pipe pressure for causing the usual operations of the train brakes, and a manually controlled means for 65 causing each of said controlling mechanisms

to establish simultaneously the same condition of brake pipe pressure.

18. Apparatus for the control of the brakes of a vehicle including a brake controlling mechanism capable of producing the "release", "running", "lap", "service" and "emergency" 70 functions of the vehicle brakes, electroresponsive means associated with said brake controlling mechanism selectively responsive to currents of different characteristics for causing said brake controlling mechanism to produce the different brake functions, a current source capable of supplying currents of different characteristics 75 to said electroresponsive means, and means to select the characteristic of the current supplied by said source and thereby determine the brake function produced.

19. In a fluid pressure train braking system, the combination with a brake pipe and 80 an engineer's brake valve device on the locomotive having positions for varying the brake pipe pressure, of an auxiliary brake controlling means on a car of the train comprising a local and independent source of fluid pressure as well as a plurality of valves each 85 operable to vary the brake pipe pressure and corresponding in number with the positions of the engineer's brake valve device, and means responsive to the movement of the 90 brake valve device to its different positions for effecting the operation of said valves.

In testimony whereof I affix my signature.
LARS O. GRONDAHL.
